(57) CLAIM

I claim the ornamental design for a shoe, as shown and described.

DESCRIPTION

FIG. 1 is a front view of a shoe showing my new design;

FIG. 2 is a side view thereof;

FIG. 3 is another side view thereof;

FIG. 4 is a top view thereof;

FIG. 5 is a back view thereof; and,

FIG. 6 is a bottom view thereof.

The broken lines in the drawings show portions of the shoe that form no part of the claimed design. Color forms no part of the claimed design.

1 Claim, 6 Drawing Sheets
